G. E. BISHOP,
AUTOMOBILE INCLOSURE.
APPLICATION FILED JAN. 9, 1922.

1,425,445.

Patented Aug. 8, 1922.

UNITED STATES PATENT OFFICE.

GEORGE E. BISHOP, OF CLEVELAND, OHIO.

AUTOMOBILE INCLOSURE.

1,425,445.

Specification of Letters Patent. Patented Aug. 8, 1922.

Application filed January 9, 1922. Serial No. 528,100.

To all whom it may concern:

Be it known that I, GEORGE E. BISHOP, a citizen of the United States, resident of Cleveland, county of Cuyahoga, and State of Ohio, have invented new and useful Improvements in Automobile Inclosures (Case T), of which the following is a specification, the principle of the invention being herein explained, and the best mode in 10 which I have contemplated applying that principle, so as to distinguish it from other inventions.

My invention relates to vehicle inclosures and particularly to apparatus of this character intended to be mounted upon automobile doors so as to ride in and out with the latter as they are opened and closed. The particular improvements of this application reside in the new and improved means 20 for swiveling and shortening the supporting rod so as to allow the latter to be collapsed and the inclosure folded or rolled for storage.

The annexed drawing and the following 25 description set forth in detail certain means embodying my invention, the disclosed means, however, constituting but one of the various mechanical forms in which the principle of the invention may be employed.

30 In said annexed drawing:

Figure 1 represents a side elevation of my new and improved inclosure;

Figure 2 represents a fragmentary elevation, upon an enlarged scale, of certain elements shown in Figure 1;

Figure 3 represents a longitudinal horizontal section taken in the plane indicated by the line III—III, Figure 2;

Figure 4 represents an elevation taken 40 from the plane indicated by the line IV—IV, Figure 2; and

Figure 5 represents a fragmentary elevation of a form of inclosure embodying a modified type of supporting rod.

Referring to the annexed drawing in which the several elements are indicated in the various views by the same respective ordinals, I have suggested suitable curtain fabric by the ordinal 1 within which are incorporated transparencies 2 and 3, respectively, disposed in the door heading and laterally of the door heading. Of course, a type of inclosure might be used which is 50 disposed above the door only, so that in that event the transparency 3 and the fabric section containing the same would be dis-

pensed with. Adjacent the upper and lower edges of the fabric, and preferably consisting of narrow flat metal rods and preferably incorporated in the fabric, are longitudinal strengthening members 4 and 5 extending preferably from the opening edge 1' of the inclosure rearwardly to a point adjacent the breaking edge of the inclosure, which breaking edge is in the plane containing the vertical projection of the hinges of the door 7 upon which the inclosure is designed to be mounted and with which it travels as it is opened and shut. This mounting of the inclosure is effected by means of a vertically-disposed supporting rod 6 adapted to register within a socket secured to the door 7 or preferably disposed within the upper edge of the door. To the end that the supporting rod may have a swivel action relatively to the fabric preliminarily to a shortening of the same so that it may be collapsed and rolled in the fabric for storage, I form the 70 rod of a plurality of elements. A rod tip 8 is pivotally secured to the fabric 1 adjacent the upper edge of the latter and preferably secured also to the upper longitudinal strengthening member 4, this tip 8 having a tubular recess 9 pivotally receiving the upper end of the supporting rod proper 6.

An arm 10 is pivotally secured at the point 10' to the fabric 1 and adjacent the lower edge of the latter and preferably also secured to the lower longitudinal strengthening member 5, this arm 10 being formed at its upper end into a bracket having a tubular section 11 adapted rotatably to receive the supporting rod proper 6. This tubular section 11 of the arm 10 is formed with communicating horizontal and vertical grooves 12 and 13, as plainly shown in Figures 2, 3 and 4. Secured to the supporting rod 6 and intersecting the groove 12, in the position 90 shown in Figure 2, for instance, is a pin 14. When it is desired to collapse the inclosure so as to roll or fold the same for convenient storage, assuming that the inclosure has been removed from the door 7, the rod 6 can be turned to allow the pin 14 to drop into the recess 13, thus in effect shortening the upper part of the rod so that it drops from the tip 8, and can then be turned down into any desired position for storage, as illustrated by the dotted lines in Figure 1.

In the form of inclosure shown in Figure 5, I have provided modified means for connecting the rod tip 8 to the upper longi-

tudinal strengthening member 4 and allowing for the relative movement of this rod tip 8 and the supporting rod section 6. These modified means are particularly shown, described and claimed in my pending application for automobile inclosures (Case S), Serial No. 530574. These modified means consist in forming the upper end of the tip 8 with an open-ended vertical recess 17 which receives the longitudinal strengthening member 4, in the assembled condition of the inclosure. Then when the supporting rod is shortened, the rod as a whole is removed from the strengthening member 4 instead of simply removing the rod section 6 from the tip 8, as shown in Figure 1. In this type of inclosure shown in Figure 5, for the purpose of permanently securing together the rod section 6 and the tip 8, and at the same time allowing for the relative movement of the same to provide for shortening the rod, I form the rod section 6 with a reduced upper end portion 16 formed with a peripheral groove 18 within which registers an inwardly extending guiding lug 15 formed upon the tubular portion 9 of the tip 8.

I utilize, with my improved inclosure, valance elements 19 and 20 shown and described by me in many other patent applications and particularly patented to me in U. S. Patent No. 1,244,692.

The swivel movement of the rod 6 afforded by the elements 8 and 9, and tubular section 11 with groove 12, also relieves the inclosure, when mounted for duty, of many strains to which it would otherwise be subjected as the door 7 is opened and closed. This relief is afforded by reason of the pivotal movement which the inclosure has, relative to the rod section 6. It is evident that the section 11 can travel around the rod 6 to allow for any necessary adjustment of the lower edge of the inclosure relatively to the supporting rod 6, the groove 12 travelling over the pin 14. This adjustment will be accompanied by any necessary co-operative adjustment of the upper edge of the inclosure, due to the possible pivotal movements of the rod tip 8 relative to the rod 6.

What I claim is:

1. An automobile inclosure adapted to be mounted upon the automobile door, comprising suitable curtain fabric; strengthening members disposed longitudinally of the fabric; a vertically-disposed combination swivel and shortening member pivotally secured at one point to said fabric and at another point separably secured to said fabric, the part of said stretching member which is pivotally secured to said fabric being formed with a tubular section having a transverse recess and a communicating longitudinal recess, a portion of said shortening member consisting of a supporting rod formed with

a pin intersecting said recesses, said tubular section receiving said rod.

2. An automobile inclosure adapted to be mounted upon the automobile door, comprising suitable curtain fabric; strengthening means consisting of a pair of horizontally arranged oppositely disposed rigid tension members; a vertically-disposed combination swivel and shortening member pivotally secured to the lower of said tension members and separably secured to the upper of said tension members, the part of said shortening member which is pivotally secured to said lower tension member being formed with a tubular section having a transverse recess and a communicating longitudinal recess, a portion of said shortening member consisting of a supporting rod formed with a pin intersecting said recesses, said tubular section receiving said rod.

3. An automobile inclosure adapted to be mounted upon the automobile door, comprising suitable curtain fabric; strengthening members disposed longitudinally of the fabric; a vertically-disposed combination swivel and shortening member having two separable parts respectively pivoted to the fabric adjacent the upper and lower edges of the latter, said parts having, respectively, a journal portion and a co-operating recess whereby they are longitudinally fixed but rotatable relatively, one of said shortening member parts being formed with a tubular section having a transverse recess and a communicating longitudinal recess, a portion of said last-mentioned part consisting of a supporting rod formed with the aforementioned journal surface and with a pin intersecting said communicating recesses, said tubular section receiving said rod.

4. An automobile inclosure adapted to be mounted upon the automobile door, comprising suitable curtain fabric; strengthening means consisting of a pair of horizontally arranged oppositely disposed rigid tension members; a vertically-disposed combination swivel and shortening member having two separable parts respectively pivoted to said tension members, said parts having, respectively, a journal portion and a co-operating recess whereby they are longitudinally fixed but rotatable relatively, one of said shortening member parts being formed with a tubular section having a transverse recess and a communicating longitudinal recess, a portion of said last-mentioned part consisting of a supporting rod formed with the aforementioned journal surface and with a pin intersecting said communicating recesses, said tubular section receiving said rod.

Signed by me this 23rd day of December, 1921.

GEORGE E. BISHOP.
